UNITED STATES PATENT OFFICE

162,187

COMBINED STAPLER AND FILE MARKER

Willard H. Lane, Long Beach, Calif.

Application February 28, 1950, Serial No. 8,210

Term of patent 14 years

(Cl. D74—1)

To all whom it may concern:

Be it known that I, Willard H. Lane, a citizen of the United States of America, residing in the city of Long Beach, in the county of Los Angeles, State of California, have invented a new, original, and ornamental Design for a Combined Stapler and File Marker, of which the following is a specification, reference being had to the accompanying drawing, forming a part thereof.

Figure 1 is a perspective view of my combined stapler and file marker, showing my new design, the broken lines being for illustrative purposes only;

I claim:

The ornamental design for a combined stapler and file marker, substantially as shown and described.

WILLARD H. LANE.
